ATTORNEY

UNITED STATES PATENT OFFICE.

ORA I. VAN SCHOICK, OF PONTIAC, MICHIGAN.

LAST.

1,199,946.

Specification of Letters Patent.

Patented Oct. 3, 1916.

Application filed May 19, 1915. Serial No. 29,066.

To all whom it may concern:

Be it known that I, ORA I. VAN SCHOICK, a citizen of the United States, residing at Pontiac, county of Oakland, State of Michigan, have invented a certain new and useful Improvement in Lasts, and declare the following to be a full, clear, and exact description of the same, such as will enable others skilled in the art to which is pertains to make and use the same, reference being had to the accompanying drawings, which form a part of this specification.

My invention relates to lasts for boots and shoes of the hinged or jointed type and consists in the arrangements and combinations hereinafter described.

In the drawings, Figure 1, represents a vertical elevation partly in section of my construction showing the internal arrangements in the closed or used position. Fig. 2, represents the same structure in the same manner, but in position for withdrawal of the last in the usual manner. Fig. 3, is a partially longitudinal section 25 on the line X—X of Fig. 2.

Similar letters refer to similar parts.

In the drawings, A represents the toe portion of the last, B the heel portion. These are two distinct parts.

C is a joint between the two portions A and B upon which they turn respectively. This joint I prefer to make by means of an inclosed cylindrical stud D, separating the two parts, said stud preferably having an enlarged central portion formed thereon at d. The parts A and B are cut out sufficiently to permit the insertion of the stud D and thus prevent vertical displacement when they are held in position as shown 40 in the figures by the means hereinafter stated. It is obvious, however, that other forms of a joint, so-called, may be used, as for instance either the part A or part B might be cut out and the parts A and B respectively have a convex curved part to fit the concavity, a manner in which two-part lasts have been heretofore united and therefore need not be further described. All that is necessary is to hold the two parts 50 in fixed relation while they turn upon each other and means to prevent displacement.

Each of the parts A and B has a narrow central groove a, b, in a semicircular form, as shown in Figs. 1 and 2 and also as shown 55 in Fig. 3. Within this groove is placed a curved spring s which preferably is of an

oval form as shown in Figs. 1 and 2 and shown in section in Fig. 3. This spring is held in place and under longitudinal tension by two pins E, F, the pins being in such relation to the stud or pivot C that when the last is in the position shown in Fig. 1, a straight line drawn between their centers will be below the pivotal point of C and when the last is open for withdrawal, as shown in Fig. 2, a straight line intersecting the pins E and F will be above the center C. The spring being placed under tension at the time of the insertion of the pins E, and F, the consequence is that when the last is in the workable position as shown in Fig. 1, it is held under strong tension from departing from that position, but when the last is open for withdrawal, as shown in Fig. 2, it is also held by the spring in an equivalent manner, the spring necessarily being strained when the intersecting line passes the center C. The spring being flat and filling the grooves or slots a and b with a fairly close fit, it affords means for holding the parts A and B in a relative position so that there can be no motion sideways of said parts upon each other. It therefore acts as a guide as well as a spring in maintaining the position of the parts in the correct position.

The mode of operation of this device is evident from the foregoing description.

It is obvious that the spring s may be made of any reasonable desired tension so as to produce an effectual resistance to any accidental force which would tend to shift the parts from one position to the other. It is also evident that it would, by means of its engagement of the pins E and F, hold the two parts A and B of the last from separation.

What I desire to claim is:

1. In a last of the type described, the combination of a toe and heel piece arranged to turn respectively upon a common pivot, an elliptical spring located in a vertical plane and uniting the two parts of the last, and means for holding the spring in operative engagement with each part respectively, which means is so located with reference to the pivotal turning point that the spring is strained in varying the position of the parts from one limit of movement to the other.
2. In a last of the type described, the combination of a toe and heel piece ar-

ranged to turn respectively upon a common pivot and having vertical slots, a spring of an elliptical shape located vertically and uniting the two parts, and means for holding the spring in operative engagement with each part respectively, which means is so located with reference to the pivotal turning point that the spring is strained in varying the position of the two parts from one limit of movement to the other.

3. In a last of the type described, the combination of a toe and heel piece arranged to turn respectively upon a common pivot and having vertical slots, and a spring of an elliptical shape located vertically, unit-

ing the two parts, closely engaging in said vertical slots in the toe and heel pieces and forming a guide therefor, and pins so located with reference to the pivotal turning point and so engaging the spring that the spring is strained in varying the position of the parts from one limit of movement to the other.

In testimony whereof, I sign this specification in the presence of two witnesses.

ORA I. VAN SCHOICK.
